STRIPPING CYLINDER

Hubert Charles Marie Henri Duesberg, Heusy, Belgium, assignor to Leon Jules Antoine Duesberg and Henri Hubert Marie Duesberg, both of Liege, Belgium

Application January 23, 1951, Serial No. 207,391

Claims priority, application Belgium April 20, 1950

3 Claims. (Cl. 19—108)

1

My present invention relates to means for the permanent stripping of the main cylinder of carding machines for textile fibres of the kind in which use is made of a stripping roller or cylinder which is placed under the main cylinder at the side opposite the doffer the clothing of said stripping roller penetrating into that of the main cylinder and said roller rotating at a greater speed and in the same sense as the latter.

The known devices make the obtaining of certain advantage possible and in particular a reduction in the number of strippings, an increase in production economy in material and improvement in the regularity of the web or fleece.

On the other hand as at present carried out they give rise to certain disadvantages.

The clothing is usually made as a band the dense parts of which are spaced and which is wound round a stripping cylinder or roller and this results consequently in an irregular lengthening of this band so that the dense parts are not always localised exactly on the same generatrix of the stripping cylinder.

Another disadvantage is that in order to replace the clothing it is necessary to remove the stripping cylinder from the carding engine and afterwards replace it again in position.

The object of the present invention is to remove these disadvantages and particularly to make the replacement of the clothing possible whilst the stripping cylinder is in its working position on the card.

For this purpose, according to the invention the stripping cylinder has on its periphery longitudinally extending metal plates which are arranged along generatrices of the cylinder or along helices of fixed pitch and which are covered with a clothing secured thereto in a manner similar to that of securing the clothing to card flats.

My invention is illustrated in the accompanying drawings in which:

Fig. 1 is a transverse section of one of the metal plates showing means for affixing it to the stripping cylinder.

Figures 2 and 3 are respectively a vertical and horizontal cross section showing a stripping cylinder provided with metal plates according to the invention.

Figure 4 is a plan view of the foundation of the clothing from below showing the arrangement of the staples forming the wire teeth.

Figure 5 relates to a modification.

Referring to Fig. 1, one of the longitudinally extending metal plate members is designated 1. A card clothing extends along the plate mem-

2

ber and comprises a base or foundation portion 2 from which wire teeth 3 extend radially outwardly. The base 2 of the clothing is secured to the plate member 1 by a pair of channel members 4 which extend along opposite sides of the plate member 1 and comprise upper and lower radially spaced arm portions which embrace edge portions of the plate member 1 and the base 2 of the card clothing for securing the card clothing to the plate member.

Referring to Figs. 2 and 3, the plate members 1 are secured by fastening means such as bolts 5 in threaded engagement with nuts 6 to flange portions 9 of supporting members 10 which are radially apertured to receive the bolts 5. The flange portions 9 are recessed so that the channel members 4 cannot move laterally away from the plate members and release the card clothing. Moreover, the inner arm portions of the channel members 4 which embrace edge portions of the inner surface of the plate member 1, are clamped between the plate members 1 and the outer surface of the flange portion 9 by the action of the bolts 5, thus further securing the assembly of the card clothing to the plate member.

The supporting members 10 are of circular configuration and are disposed in spaced relationship along a shaft 12. The supporting members 10 comprise hub portions 11 which are keyed or otherwise fixed to the shaft 12 for rotation therewith. The supporting members 10 extend radially outwardly from shaft 12 and curved metal sheets 8 are mounted thereon intermediate the plate members 1 to form a closed hollow metal cylinder.

A feature of the invention is that the clothing may have the staples forming the wire teeth 3 arranged in threes so that the teeth form a series of regular designs. The clothing is thus arranged on the plates according to a design which is repeated every three teeth.

In Figure 4 of the accompanying drawings the portions 7 of each staple forming the wire teeth 3 are arranged as shown that is, if in a transverse direction two adjacent groups 8¹ and 8² each comprising three staples are considered, the portions 7¹—7⁴, 7²—7⁵, 7³—7⁶ of the corresponding row in each of the groups occupy positions such that the locations of their teeth 3 are situated at the corners of a square (squares C).

The foundation may be made on a band machine utilising the machine only for the formation of the perforations at the positions indi-

cated at P (Figure 2) and the staples then set at the position shown at 7 by usual or suitable means.

Figure 5 shows a form of embodiment in which the metal plates are arranged along helices of fixed pitch.

What I claim is:

1. A carding cylinder of the class described, comprising: a main supporting shaft, a plurality of supporting members disposed in spaced relationship along said shaft and fixed thereto for rotation therewith, said supporting members extending radially outwardly therefrom and being provided at their outer portions with radially apertured flange portions, a plurality of plate members extending longitudinally of said shaft, fastening means securing said plate members to said flange portions and cooperating with said apertures, a card clothing extending along each of said plate members and comprising a base portion covering the width of said plate member, and a pair of channel members extending along opposite sides of each of said plate members and comprising radially spaced arm portions which embrace edge portions of each plate

member and the base of each card clothing for securing said clothing to said plate member.

2. A cylinder according to claim 1, in which said flange portions are recessed and said plate members are disposed in said recesses, whereby disengagement of said channel members by lateral movement away from said plate members is prevented.

3. A cylinder according to claim 1, further comprising curved metal sheets extending between said plate members and secured to said supporting members to form a closed hollow cylinder.
